UNITED STATES PATENT OFFICE.

JOHN D. MURRAY, OF SAN FRANCISCO, CALIFORNIA.

AIR BRUSH.

Application filed May 3, 1926. Serial No. 106,356.

This invention relates to that type of structure employed primarily for the application of paint or other liquid coating materials to surfaces by the use of air under pressure and is commonly termed an air brush or spray gun.

Among the principal objects of this invention are the utilization of what may be commonly termed a crossed coupling as the body 10 of the apparatus, whereby the cost of manufacture of the body is reduced to a minimum; the utilization of a relatively light body, approximately from the center of which depends a handle constituting a fluid feed duct; the provision of a simple trigger mechanism in advance of the handle for actuation to operate the tubular nozzle whereby the latter controls the discharge of the intermixed stream of liquid and air in accordance with the degree of operation of the trigger. A further object is to provide a construction wherein a normal liquid supply may be readily cut off by a predetermined movement of the discharge nozzle and 25 a different liquid supply connected with the nozzle readily adapting the apparatus to the application of different liquids, or the same liquids in different colors without any material change and with the loss of the minimum time.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein—

Figure 1 is a view in side elevation.

Figure 2 is a view in top plan.

Figure 3 is a longitudinal sectional view on the horizontal plane taken on line 3—3 of Fig. 4, disclosing the interior arrangement and formation of the discharge nozzle and its associated parts.

Figure 4 is a view similar to Figure 3 taken on line 4—4 of Fig. 3.

Figure 5 is a view in elevation of the discharge tip.

Fig. 6 is a view in elevation of the ported disk intermediate the air and liquid delivery ports.

Figure 7 is a vertical sectional view on line 7—7 of Fig. 4.

Figure 8 is a vertical sectional view of the swivel joint connection.

Figure 9 is a fragmentary detail sectional view illustrating a reservoir for supplying, by capillary attraction, liquid to the discharge nozzle when the same is axially rotated to position its liquid control port upwardly.

Referring more particularly to the several views of the drawings wherein like characters of reference designate corresponding parts, 1 indicates a liquid supply pipe, to the upper end of which is connected the branch 2 of a tubular circumferentially T-shaped body 3. The horizontal portion of the T-shaped body is tubular as at 4, the forward end of which is substantially full open and the rear end of which is provided with a reduced opening 5. The liquid supply pipe 1 communicates with the interior of the horizontal portion of the tubular body 3 through port 6, and to the rear end of the horizontal portion of the tubular body 3 is detachably coupled a flexible pipe 7 for conducting air under pressure thereinto. The pipe 7 is connected with the end of the body by a collar 8 resting on a shoulder 9 of the pipe and the body of the collar is threaded to the flange 10 surrounding the reduced opening 5. Disposed concentrically within the flange 10 is a conical projection 11 immediately surrounding the reduced opening 5 and for reception within the end of the flexible pipe or hose 7. It will be observed that the conical member 11 affords a spreader for extending the portion of the hose 7 received between the members 10 and 11 against the respective walls of the members when the collar 8 is tightly threaded on to the flange 10.

Linearly reciprocable longitudinally of the tubular body 3 with its outer end projecting beyond the end of the tubular body is a tubular discharge nozzle A consisting of the cooperating tubular parts 12 and 13. The part 12 projects beyond the end of the tubular body 3 and reciprocates through a gland packing 14 carried at the end of the body 3. The outer end of the portion 12 of the nozzle A is threaded at 15 and detachably carries a transversely slotted spray tip

16 at its end, the latter being held in place by a threaded collar 17, which in turn threads on to a flanged filler nut 18 threaded directly to 15. Angularly from the filler nut 18 is 5 adjustably threaded on the part 12 a seep nut 19, and adjacent its inner end the part 12 is provided with a port 20 for registering with the port 6 when the discharge nozzle is reciprocated angularly from normal position. Concentrically disposed in the inner 10 end of the part 12 of nozzle A is a portion 13 of the nozzle A between the forward end of which and the port 20 is removably positioned a ported disk 21 which controls the air delivered into the member 12. A spring 15 22 surrounds the portion 13 and abuts against the wall of the tubular body 3; this spring exerting pressure will maintain the members 12 and 13 forwardly into the 20 tubular body 3. The rear end of the member 13 is laterally ported at 23 to cooperate with the wall of the reduced opening 5, said port on the rearward reciprocation of the members 12 and 13 moving beyond 25 the end of the wall of said reduced portion and affording an air inlet into the member 13.

The discharge nozzle is reciprocated 30 against the action of the spring 22 by the operation of a trigger 24 lying in advance of the pipe 1. The upper end of the trigger is bifurcated at 25, and is received between the filler nut 18 and the seep nut 19. The ends of the bifurcations 25 are ported, and in said 35 ports are received the hooked ends 26 of spring arms 27. United at their inner ends by a curved connecting portion 28, which is held by a plug 29 threaded into the bore 30 which is a continuation of the pipe 1 above 40 the point of its intersection by the tubular body 3, as in Fig. 7.

A bowed handle 31 is arcuately rotatable about the pipe 1, as in Fig. 1, and affords a 45 gripping member for reception within the palm of the hand when the gun is in use and pressure is applied to pull the trigger 24 rearwardly. The tip 16 and the ported disk 21 are readily changeable to enable the 50 best suited tip to be employed, and the disk having the proper opening to admit the required air delivery to obtain the best results.

The parts being in position as in the drawing, with the exception of Fig. 9, and air under pressure being admitted through pipe 55 7 and pipe 1 being connected to a fluid supply, the operator grasping the trigger 24 and reciprocating the discharge nozzle rearwardly from its position in Fig. 3 to that in Fig. 4, affords communication first 60 between the liquid supply and the interior of the portion 12 and the nozzle A. After this communication has been established, uncovering the port 23 enables air under pressure passing through the disk 21, to pick up the 65 liquid admitted through the pipe 1 and dis-

charge the same in a flat fan spray from the tip 16, the reciprocation to operative position of discharge nozzle being controlled solely by the operation of the trigger 24 which is held between the nuts 18 and 19. 70 Should the operator desire to cut off the liquid flow pipe 1, it is only necessary that the part 12 of nozzle A be axially rotated from its position in Figs. 4 and 7 to that in Fig. 9, the plug 29 removed, and a liquid 75 container 32 substituted therefor. With the port 20 upwardly disposed, communication through pipe 1 is interrupted and the liquid from the container 32 is utilized by the air under pressure from pipe 7.

It will be observed that the parts are readily disassembled for cleaning and after cleaning are readily assembled, that the structure is light and compact, and is adapted for general uses. In the paint line is located a ported disk 33, preferably positioned transversely of the line immediately exteriorly of port 6. The relative sizes of apertures in disks 21 and 33 positively controls the proportion of paint and air admitted 90 into the gun for intermixing therein and discharge therefrom. The disk 33, like the disk 21, may be changed and supplemented by a disk having a larger or smaller aperture as desired.

In this construction, it will be observed that the reciprocation of the member A controls both the admittance of air and admittance of liquid for discharge through the 100 nozzle tip 6.

I claim:—

1. A spray gun comprising a substantially T-shaped structure, the top consisting of a tubular body and the stem a tubular handle, a tubular discharge nozzle extended from one end of the body and lineally reciprocable longitudinally therein, said discharge nozzle provided at one end with a discharge tip and provided in its wall with ports for respectively admitting liquid and air under pressure thereinto, the liquid at a point intermediate the tip and the air supply, said body provided with liquid and air passages with which said ports are adapted to register on the lineal movement of said nozzle, means for normally maintaining said ports out of register with said passages, and a trigger between said handle and said tip for operation to actuate said nozzle against the action of said means.

2. A spray gun comprising a substantially T-shaped structure, the top consisting of a tubular body and the stem a tubular handle, a tubular discharge nozzle extended from one end of the body and lineally reciprocable longitudinally therein, said discharge nozzle provided at one end with a discharge tip and provided in its wall with ports for respectively admitting liquid and air under pressure thereinto, the liquid at a point inter-

- mediate the tip and the air supply, said body provided with liquid and air passages with which said ports are adapted to register on the lineal movement of said nozzle, means 5 for normally maintaining said ports out of register with said passages, a ported dia- phragm disposed transversely of the tubular discharge nozzle intermediate said ports, and a trigger between said handle and said 10 tip for operation to actuate said nozzle against the action of said means.
3. A spray gun comprising a substantially T-shaped structure, the top comprising a tubular body and the stem a tubular handle, 15 means for supplying separate streams of air under pressure and liquid to the tubular body, a tubular discharge nozzle extended lineally from one end of the body and reciproable longitudinally therein, said dis- 20 charge nozzle provided with ports controlling the admission thereinto of air under pressure and liquid, means for normally maintaining said nozzle to preclude the admission thereinto of streams of air and li- 25 quid, and a trigger in advance of said handle for operation to actuate said nozzle against the action of said means.
4. A spray gun comprising a substantially T-shaped structure, the top comprising a tubular body and the stem a tubular handle, 30 means for supplying separate streams of air under pressure and liquid to the tubular body, a tubular discharge nozzle extended lineally from one end of the body and reciproable longitudinally therein, said dis- 35 charge nozzle provided with ports controlling the admission thereinto of air under pressure and liquid, means for normally maintaining said nozzle to preclude the admission thereinto of streams of air and li- 40 quid, and a trigger coacting with said nozzle in advance of said handle for operation to actuate said nozzle against the action of said means.
- 45 5. A spray gun comprising a substantially T-shaped structure, the top comprising a tubular body and the stem a tubular handle, means for supplying separate streams of air under pressure and liquid to the tubular 50 body, a tubular discharge nozzle extended lineally from one end of the body and reciproable longitudinally therein, said dis- 55 charge nozzle provided with ports controlling the admission thereinto of air under pressure and liquid, means for normally maintaining said nozzle to preclude the admission thereinto of streams of air and li- 60 quid, an arm disposed parallel with the nozzle in advance of the handle, a trigger ful- crumed thereto and cooperating with the nozzle whereby on the movement of said trigger toward said handle, said nozzle is actuated against the action of said means.
- 65 6. A spray gun comprising a tubular handle and a tubular body disposed trans- versely across the handle and intersecting the same within its length, an air supply pipe connected with the lower end of the body portion, a removable plug closing the upper end of the tubular handle, a fluid supply pipe connected with one end of the handle, a tubular nozzle lineally reciproable longitudinally within the tubular body and projecting toward the other end thereof, said nozzle provided with ports for communicating with the respective supplies of liquid and air on the reciprocation of the nozzle from normal position, yieldable means for maintaining the nozzle in normal position, and a trigger depending from the nozzle in advance of the handle whereby on the movement of the trigger toward said handle, said nozzle is actuated against the action of said means.
7. A spray gun comprising a tubular handle and a tubular body disposed trans- 85 versely across the handle and intersecting the same within its length, an air supply pipe connected with the lower end of the body portion, a removable plug closing the upper end of the tubular handle, a fluid supply pipe connected with one end of the handle, a tubular nozzle lineally reciproable longitudinally within the tubular body and projecting beyond the other end thereof, said nozzle provided with ports for communicating with the respective supplies of liquid and air on the reciprocation of the nozzle from normal position, yieldable means for maintaining the nozzle in normal 90 position, an arm extended forwardly from the upper end of the supply pipe, a trigger fulcrumed at its upper end thereto and depending in advance of the handle, and a nut threaded on the nozzle and against which the trigger bears.
8. A spray gun comprising a tubular handle, a tubular body disposed transversely across the handle and intersecting the same within its length, an air supply pipe connected with the lower end of the body portion, a removable plug closing the upper end of the tubular handle, a fluid supply pipe connected with one end of the handle, a tubular nozzle lineally reciproable longitudinally within the tubular body and projecting beyond the other end thereof, said nozzle provided with ports one for communicating with the respective supplies of liquid and air on the reciprocation of said nozzle from normal position, yieldable means for maintaining said nozzle in normal position, said nozzle adapted for axial rotation within said body to position one of said ports to register with the upper end of the tubular handle, and a trigger associated with the nozzle in advance of the handle.
9. A spray gun comprising a handle and a tubular body disposed transversely across the same, an air supply leading into the body, a

fluid supply pipe connected with the body at a point in advance of the point of air admission, a tubular nozzle lineally reciprocable longitudinally within the tubular body and projected outwardly from the other end thereof, said nozzle provided with ports for communicating with the respective supplies of liquid and air on the reciprocation of the nozzle from normal position, yieldable means for maintaining the nozzle in normal position, and a trigger depending from the nozzle in advance of the handle whereby on the movement of the trigger toward said handle, said nozzle is actuated against the action of said means.

10. A spray gun comprising a handle and a tubular body disposed transversely across the same, an air supply leading into the body, a plurality of fluid supplies leading into the body at a point in advance of the point of air admission, a tubular nozzle lineally reciprocable longitudinally within the tubular body and provided with a pair of ports one for communication with the re-

spective supplies of liquid and air on the reciprocation of said nozzle from normal position, said nozzle adapted for axial rotation for positioning the liquid communicating port to selectively register with one of said liquid supplies, and a trigger associated with the nozzle in advance of the handle.

11. A spray gun comprising a handle and a tubular body disposed transversely thereof, an air supply leading into the body at a point in advance of the point of air admission, a tubular nozzle lineally reciprocable longitudinally within the tubular body and provided with a pair of ports one for communicating with the respective supplies of liquid and air on reciprocation of said nozzle from normal position, and a trigger associated with the nozzle and depending therefrom in advance of the handle.

In testimony whereof I have signed my name to this specification.

JOHN D. MURRAY.
